(57) **CLAIM**

The ornamental design for a buffer pad, as shown and
described.

DESCRIPTION

FIG. 1 is a perspective view of the buffer pad in accordance
with a first embodiment of the present invention;

FIG. 2 is a front view of the buffer pad of FIG. 1;

FIG. 3 is a rear view of the buffer pad of FIG. 1;

FIG. 4 is a right side view of the buffer pad of FIG. 1;

FIG. 5 is a left side view of the buffer pad of FIG. 1;

FIG. 6 is a bottom view of the buffer pad of FIG. 1;

FIG. 7 is a top view of the buffer pad of FIG. 1;

FIG. 8 is a perspective view of the buffer pad in accordance
with a second embodiment of the present invention;

FIG. 9 is a front view of the buffer pad of FIG. 8;

FIG. 10 is a rear view of the buffer pad of FIG. 8;

FIG. 11 is a right side view of the buffer pad of FIG. 8;

FIG. 12 is a left side view of the buffer pad of FIG. 8;

FIG. 13 is a bottom view of the buffer pad of FIG. 8; and,

FIG. 14 is a top view of the buffer pad of FIG. 8.
